UNITED STATES PATENT OFFICE.

JOSEPH JOFFRIAUD, OF SAN FRANCISCO, CALIFORNIA.

DESIGN FOR A TWINE-CUTTER.

SPECIFICATION forming part of Design No. 29,821, dated December 20, 1898.

Application filed July 2, 1897. Serial No. 643,297. Term of patent 14 years.

To all whom it may concern:

Be it known that I, JOSEPH JOFFRIAUD, a citizen of the French Republic, residing at San Francisco, in the county of San Francisco and State of California, have invented and produced a new and original Design for Twine-Cutters, of which the following is a specification, reference being had to the accompanying drawings, forming part thereof.

Figure 1 is a side elevation of a twine-cutter which embodies my design, and Fig. 2 is a front view of the same.

My invention relates to a new and original design for twine-cutters which have the general form or configuration of a bird; and the essential features thereof, as shown in the drawings, are embodied in a body portion C,

having the general shape or configuration of the body of a bird, and a head portion C', having the general shape of the head of a bird and being provided with the beak portion C², said head and body being connected by a neck portion C³. The front side of the beak and rear or under side of the beak are connected by a curved thinned or sharpened portion D. 20 The body is supported by legs B' from a base A. 25

Having thus described my invention, what I claim is—

The design for a twine-cutter, substantially as shown and described.

J. JOFFRIAUD.
